UNITED STATES PATENT OFFICE.

BERTHOLD JAHN AND ERNEST EMIL KAHL, OF NEW BRITAIN, CONNECTICUT, AS-SIGNORS, BY MESNE ASSIGNMENTS, TO GERTRUDE H. HEYN, OF COMPO COVE, WESTPORT, CONNECTICUT.

STAPLE BINDER.

Application filed May 9, 1921. Serial No. 467,936.

To all whom it may concern:

Be it known that we, BERTHOLD JAHN and ERNEST EMIL KAHL, citizens of the United States, residing at New Britain, in the county of Hartford and State of Connecticut, have invented certain new and useful Improvements in Staple Binders, of which the following is a specification.

Our invention relates to improvements in staple binders, corresponding in certain features to the device shown and described in our application Serial No. 447,224, filed Feb. 23, 1921, and the object of our improvement is simplicity and economy in construction and convenience and efficiency in use.

In the accompanying drawing:

Figure 1 is a side elevation of our improved staple binder.

Figure 2 is a plan view of the same.

Figure 3 is a view on an enlarged scale part in side elevation and part in section on the line 3—3 of Fig. 2.

Figure 4 is an elevation of the right side frame or case member as viewed from the inner face.

Figure 5 is a sectional view on a further enlarged scale on the line 5—5 of Fig. 3.

Figure 6 is a fragmentary sectional view on the line 6—6 of Fig. 3.

Figure 7 is a side elevation, on the same scale as Fig. 3, of the die holder or guide bar, and the die at one end thereof.

Figure 8 is a sectional view on the line 8—8 of Fig. 3.

Figure 9 is a sectional view on the line 9—9 of Fig. 1.

Figure 10 is a bottom view of the die and the adjacent parts of the die holder.

Figure 11 is a sectional view on the line 11—11 of Fig. 10.

Figure 12 is an end face view of the die in part broken away so as to show part of the die holder.

Figure 13 is a plan view of the blank for the die.

Figure 14 is a rear end view of the die.

Figure 15 is an isometric view of the die, the adjacent parts of the die holder being indicated by broken lines.

Figure 16 is a fragmentary view showing a plan of the front end of the casing or frame.

Figure 17 is a plan view of the plunger with the knob in part broken away.

Figure 18 is a sectional view on the line 18—18 of Fig. 17, with the fin member shown in side elevation.

Figure 19 is a plan view of the blank for the body member of the plunger.

Our improved staple binder comprises certain fundamental features of construction and operation that are similar to features that are found in the device shown and described in the application referred to above.

Thus there is the base 10 that has the anvil 11 at the front end for clenching the staples 12 in cooperation with the plunger 13 after they have been severed from the staple strip to which they are connected as supplied to the machine and are forced downwardly by the continued movement of the said plunger.

At the rear end of the base 10 is a pair of upstanding ears 14, in spaced relation, that support the pivotal pin 15.

The base 10 serves as the fixed member, and a moving member, designated generally by the character 16, is operatively connected thereto by the pivotal pin 15.

A pair of ways 17 at the front part of the moving member 16, positioned in spaced relation, engage with the side edge portions of the plunger 13 and serve to guide the plunger in its upward and downward movement.

The filler piece 18 that extends along the bottom of the moving member 16, and is opposed to the base 10, is positioned between the two side plates 19 of the frame or casing; has the upper portion 20 reduced in width so as to serve as the guide for the staple strip; supports by its front end the die 21, which latter is in the form of a separate and removable piece; supports by the lower portion 22 suitable dowel pins 23 for positioning the side plates 19; and has the rear end portion extended between the ears 14 and pivotally supported by the pin 15.

The said bottom portion 22 also has holes for the two holding screws for holding the side plates 19 in place, comprising the screw 24 at the rear and the front screw 25.

As will be described, the front screw 25 serves also as the means for holding the die 21 in place.

The upper part of the casing for the moving member 16 is formed by the side plates 19 which have their body portions posi-

tioned in spaced relation to provide a housing for the staple moving or feeding mechanism that cooperates with the plunger 13. The form of the said upper part of the casing is generally triangular, with a sloping or inclined rear and upper wall 26, and the closure for the said rear and upper portion is provided by means of inwardly turned, opposed flanges 27 on the side plates 19.

10 At the upper, front part of the casing, being at the upper ends of the ways 17, is a seat 28 for a spring 29 that cooperates with a knob 30 at the upper end of the plunger 13 so as to tend to hold the said plunger in the uppermost position.

15 The staple strip feeding mechanism is similar to that shown and described in the application above referred to, being actuated by a lug 31 on the plunger 13, and comprising a feeding pawl 32 and a holding pawl 33.

20 The feeding pawl 32 is supported by a pivotally supported dog 34, the latter having a lug 35 cooperating with the lug 31 on the plunger 13, and a spring 36 serves to position the said feeding pawl 32 relatively to the dog 34.

25 A spring 37 serves to position the holding pawl 33.

30 The features involved in the present invention comprise indentation of the body portion 38 of the side plates 19; the construction of the filler piece 18 of sheet material; the construction of the die 21 of sheet material; the construction of the plunger 13 of sheet material, comprising the plunger body 39 as well as the fin plate 40 that has the lug 31; utilizing the said indentation of the body portion 38 as part 35 of the way 17 for guiding the plunger 13 and also as a stripper for the upper, guide portion 20 of the filler piece 18; and certain other features incidental to those mentioned.

40 As to the indented body portion 38 of the side plate 19, this comprises the major portion of the plate, which is made of sheet metal, so that the indentation serves to reinforce and stiffen the side plate generally.

45 The form may be substantially triangular, as shown, and conforming to the general form of the side plate 19, with the major portion of the upper, rear indented edge 41 inclined and in a manner similar to the flange 27 and wall 26.

50 The bottom edge 42 of the indented body portion 38 is straight; extends alongside the upper, guide portion 20 of the filler piece 18 so as to be positioned above the staple strip mounted thereon and serves as a guide for the said staple strip as it is fed along towards the plunger 13 and die 21; and the part of the said bottom edge 42 adjacent the die 21 is adapted to engage with the staple strip in case of a lifting movement

thereof during the upward or return movement of the plunger 13, serving thus as a stripper.

55 The staple strip is of U-shape, as is common, and the two bottom edges 42 engage with the side edges or corners thereof, one on each side, during such stripping of the staple strip, the effect of such stripping being to prevent clogging of the machine.

60 The front edge of the indented body portion 38 is utilized to serve as the rear wall 43 of the way 17, positioned in opposition to the rear face of the plunger body 39. Only part of the said front edge is used for this purpose, as shown. This for the reason that a relatively sharp structure, with a pronounced corner is desirable for backing the plunger 13 in its movements, and that it is unnecessary operatively and from a structural standpoint undesirable to provide such a superior structure for the entire length of the said front edge that is opposed to the plunger 13.

65 In the structure shown the rear wall 43 of the way 17 may be described as of interrupted form, with an active portion at the top and a second active portion at the bottom, the portion 44 of the said front edge intermediate these parts being of rounded form, so as to clear the plunger 13 generally. The rear wall 43 terminates at the top corner 45 of the indented body portion 38 at the upper end and at the lower end meets the corner 46 at the junction with the bottom, guide edge 42.

70 The filler piece 18 is made of sheet metal, bent generally into U-shape, the upper portion 20 being reduced relatively to the lower portion 22, there being a longitudinally directed shoulder 47 on each side at the junction of the two portions. Thus the bottom portion 22 consists of two similar side walls that extend downwardly from the shoulders 47, separated by the open space 48 and which fit between the ears 14 that provide the support for the pivotal pin 15.

75 The die 21 is fitted to the front end of the filler piece 18; has side walls 49 that fit within the open space 48 in the bottom portion 22 of the said filler piece 18; has at the front end a plate-like, upwardly directed cutter plate 50 that abuts against the opposed end face 51 of the filler piece 18; and has at the lower portion a base plate 52 that extends along the bottom and, in use, rests on the anvil 11.

80 The cutter plate 50 is shaped to correspond to the end face 51 and serves as the active die or cutter for severing the individual staples 12 from the staple strip in cooperation with the plunger 13, the cutting edges being located at the upper, front corner 53 of the cutter plate 50 and the lower rear corner or edge 54 of the said plunger 13.

85 The die 21 may be made of a single piece

of sheet material from a blank such as is shown in Fig. 13 that has at the front end the portion that serves as the cutter plate 50 and at the rear end the back plate 55 that contains material that is utilized for forming the bottom 52 and the side walls 49. The cutter plate 50 and back plate 55 are connected at the middle along the line 56 at which the material is bent in the shaping 10 operation and they are separated on each side of the said line 56 by a pair of side slits 57. The back plate 55 is operated upon by a combination of bending and swaging so as to bring the side walls 49 in the upright 15 position relatively to the bottom or base 52, the two lines 58 indicating approximately the lines of connections of these parts, and also, as indicated by the curved line 59 connecting the side lines 58, there is material 20 at the rear end that serves to provide a reinforcing wall 60.

The side walls 49 are provided with suitable holes 61 in alignment for the front holding screw 25 that holds the side plates 25 19 in place and also serves to hold the die 21 in the operative position. Also, the side walls fit against the undersides of the shoulders 47 in the filler piece 18.

The rear wall 43 of the way 17 has been 30 described, corresponding to the front edge of the indented body portion 38. A flat or plain border encloses the said body portion 38. The part 62 of the said flat border portion in front of the rear guide wall 43 constitutes the side wall of the way 17. The front wall of the way 17 is formed by an inwardly turned flange 63 on the side plate 19, being turned inwardly from the edge of the side wall 62 just described.

40 At the upper end of the way 17 is the seat 28 for the spring 29, as mentioned, and the front portion of the said seat 28 is in the form of a forwardly directed finger 64 that is integral with the inner edge of the guide flange 63.

The engagement of the ways 17 with the plunger body 39 is confined to the edge portions 65 thereof.

50 The said plunger body 39 is reinforced longitudinally by means of a rib 66, projected forwardly relatively to the said edge portions 65. In the formation of the rib 66 a groove 67 is provided on the rear face, and the said groove is utilized as a seat for the fin structure 40, which is embedded therein edgewise. A plurality of rivets 68 integral with the fin structure 40 may be used to hold the same in place.

55 In addition to the integral rivets 68 the fin structure 40 has at the upper end a forwardly directed lug 69 that extends through a slot 70 in the plunger body 39 and on the rear or inner side or edge has intermediate its length a shoulder 73 for cooperating 65 with the opposed portion 74 of the casing

for limiting the upward movement of the plunger.

Thus at the upper end of the plunger 13 is provided a seat 71 for the knob 30, comprising the plunger body 39 and the fin 70 structure 40 at right angles, one to the other, the edges of these parts being opposed to the said knob 30. Upwardly extending rivets 72, integral with the plunger body 39, serve to hold the knob 30 in place. 75

As described, the under face of the knob 30 makes contact with the upper, tip end of the plunger body 39 and also the fin structure, wherefore, when a blow is given to the knob to drive the plunger 13 the knob serves as 80 the means for transmitting the effect of the blow directly to these parts of the plunger.

We claim as our invention:—

1. A staple binder comprising a base, a member pivoted thereto comprising a casing composed of a pair of opposed sheet metal side plates, a filler piece positioned between the lower portions of the side plates, a die at one end of said filler piece, the upper portion of said filler piece being reduced in width so as to serve as guide for a staple strip, feed devices in said casing, a plunger reciprocating in said casing and provided with a cutting edge for cooperation with said die and means for operating said feed devices, a spring seated upon said casing tending to elevate said plunger, and said plates comprising flat border portions and centrally indented portions arranged to provide flanges along the lateral edges of said plunger and flanges adjacent the filler piece for holding a staple strip thereon. 95

2. A staple binder as described in claim 1 in which the said filler piece is made of a piece of sheet metal of elongated form, bent along longitudinal, parallel lines so as to have an approximately U-shape of cross-section, and is provided with shoulders at the junction of the upper, reduced portion and the lower portion. 105

3. In a staple binder, a filler piece operating as a way or support for the staple strip and comprising a piece of sheet metal of elongated form, bent along longitudinal, parallel lines so as to have an approximately U-shape of cross-section, and with shoulders at the sides denoting the junction of the lower portion and an upper, reduced portion and a die cooperating with one end portion of said filler piece, said die having a supporting portion that is housed in said lower portion. 115

4. In a staple binder as described in claim 3 in which said supporting portion is opposed to the inner and lower sides of said shoulders. 120

5. In a staple binder as described in claim 3 in which the supporting portion for the die which is housed within the lower portion of the filler piece includes a pair of side plates which are opposed to the side faces of the 125 130

filler piece and a holding screw extending through the side faces of the filler piece and the side plates of the die supporting portion.

6. In a staple binder, a casing, a filler piece extended along the lower side of the casing to serve as a guide for the staple strip and a support for the side portions of the said casing, the said filler piece being made of a single piece of sheet metal, bent approximately into U-shape cross-section, with longitudinally directed shoulders at the junction of the upper, staple strip receiving portion and the lower portion and a die having a supporting portion that telescopes with one end portion of said filler piece, whereby each is adapted to serve as a reinforcement of the other.

7. In a staple binder, a filler piece constituting a part of the casing structure and having a die at one end, the said die being in the form of a separate piece, having a cutter-plate portion that fits against the end of the filler piece and having other supporting portions that serve as supports for the said cutter-plate portion, the said supporting portions and the end portion of the filler piece being constructed and arranged to overlap for connecting the die to the filler piece and said die being formed of a single piece of material of generally skeleton form.

8. In a staple binder as described in claim 7 in which a single screw serves as the means for holding the die in place at the end of the filler piece, and the parts that receive the said screw comprise plate-like portions that overlap one another and have holes in registration for receiving the screw.

9. In a staple binder as described in claim 7 in which the said casing has side plates that are positioned one on each side of the said filler piece, and a screw serves as holding means for holding the said side plates in position and also serves to hold the said die in the operative position on the said filler piece.

10. In a staple binder having a die that is positioned at one end of a filler piece, the said die being formed of a piece of sheet material, having a cutter plate with a cutting edge at one end, and having connected to the said cutter-plate a supporting structure that is adapted to be connected to the said filler piece and said cutter-plate being positioned in abutment with the end face of said filler piece.

11. In a staple binder, a filler piece having

an open end, a die having a supporting portion that telescopes into the said open end, and a cutter plate positioned at one end of said supporting portion, and said cutter plate and supporting portion being integrally connected by opposed edge portions.

12. In a staple binder having a plunger that is operatively mounted for reciprocating in a casing and has a cutting edge for cooperating with a die that is fixed in the said casing, the said plunger having a plunger body that is provided with the said cutting edge, the said plunger body being made of sheet material and said plunger body having a longitudinally directed reinforcing rib and a fin structure, also of sheet material, extending from adjacent the lower end of said body upwardly along one face thereof for the major portion of the length of said body, said fin structure being secured to said face.

13. In a staple binder comprising a plunger having a plunger body that has a cutting edge and a fin structure mounted on the said body and serving to operate feed mechanism for feeding a staple strip, the said plunger body having a longitudinal rib on one face and having on the opposite face a groove to conform to the said rib, and the said fin structure being seated in the said groove.

14. In a staple binder as described in claim 12 in which the plunger body has a groove and the fin structure is seated in said groove.

15. In a staple binder as described in claim 13 in which the said plunger body and fin structure form at their upper ends a seat for a knob.

16. In a staple binder, a plunger body having a fin structure mounted on one face, the upper ends on the said body and fin structure terminating in a seat for a knob, and the said fin structure having at its upper end a lug that extends through a slot in the plunger body so as to provide an extension of the said seat on the side of the other face of the plunger body.

17. In a staple binder, a plunger body and a fin structure mounted on one face thereof, the plunger body having a slot at the upper end, and the fin structure having an extension in the form of a lug that fits and extends through the said slot.

BERTHOLD JAHN.
ERNEST EMIL KAHL.
